EDWIN LEHR, OF PITTSBURGH, PENNSYLVANIA, ASSIGNOR TO WESTINGHOUSE ELECTRIC & MANUFACTURING COMPANY, A CORPORATION OF PENNSYLVANIA.

FURNACE-REGULATOR SYSTEM.

1,320,071.

Specification of Letters Patent.

Patented Oct. 28, 1919.

Application filed March 19, 1919. Serial No. 283,625.

To all whom it may concern:

Be it known that I, EDWIN LEHR, a citizen of the United States, and a resident of Pittsburgh, in the county of Allegheny and State 5 of Pennsylvania, have invented a new and useful Improvement in Furnace-Regulator Systems, of which the following is a specification.

My invention relates to regulator systems 10 and particularly to regulator systems for governing the operation of electric furnaces.

One object of my invention is to provide a furnace-regulator system that shall be controlled either manually or automatically to 15 maintain a substantially constant current flow through, or to maintain a substantially constant power input into, or to maintain a substantially constant voltage across, a furnace in a simple and an economical manner, without any abrupt circuit changes.

In operating electric furnaces, and particularly in operating electric furnaces that are provided with resistors having negative temperature coefficients, it is essential to 25 guard against overheating the furnace by reason of any abnormal current flowing through the resistors. Thus, in case the load on a furnace is reduced and the heat taken by radiation from the furnace resistor is reduced, then the resistor, by reason of its 30 having a negative temperature coefficient, is liable to become overheated and permit an excessive current flow through the furnace. Moreover, it is very desirable, in operating 35 an electric furnace, to change the current flow through, or the power input into, the furnace without breaking the furnace circuit and without any abrupt circuit change.

In a furnace-regulator system constructed 40 in accordance with my invention, means is provided for governing the power input into the furnace, either manually or automatically, in accordance with the current flowing through the furnace, in such manner as to insure against overheating of the furnace and, moreover, means is provided for varying the power input into the furnace without causing any breaks or abrupt changes in the furnace circuit.

The furnace-regulator system utilized for 45 practising my invention embodies a main transformer provided with a secondary winding connected to the furnace resistor and a primary winding having one terminal 50 connected to one side of the supply circuit

and a plurality of taps which are selectively connected to the other side of the supply circuit by means of an auxiliary transformer. The system is further provided with a selector switch, an induction regulator, and a suitable transfer switch.

The auxiliary transformer comprises a primary winding and a secondary winding having two coils each of which has one terminal thereof successively connected, by the transfer switch, to one side of the supply circuit. The selector switch serves to connect the other terminals of the two secondary coils of the auxiliary transformer to selected taps extending from the primary 70 winding of the main transformer. The induction regulator is energized by the main transformer and is so connected to the primary winding of the auxiliary transformer as to control the voltage which is impressed 75 on the two secondary coils of the auxiliary transformer.

The selector switch, the transfer switch and the induction regulator are geared to an electric motor so that the transfer switch 80 and the revolving parts of the induction regulator make one complete revolution during the time the arms of the selector switch are passing from one switch segment to an adjacent switch segment. The motor is preferably operated in a forward and in a reverse direction under the control of two relays. The relays may be controlled either manually, by means of push buttons, or automatically, by a main control magnet, 90 which is energized in accordance with the current flowing through the furnace.

In transferring the supply-circuit connection from one primary tap of the main transformer to a second tap in order to 95 change the power input into the furnace, the transfer switch is first adjusted to a predetermined position for connecting one secondary coil of the auxiliary transformer to a contact arm of the selector switch, and the induction regulator is adjusted to a position for impressing a zero voltage on the two secondary coils of the auxiliary transformer. The voltage impressed on the two secondary 100 coils of the auxiliary transformer is increased to a value equal to one half the voltage existing between two adjacent primary taps of the main transformer, and then the two secondary coils of the auxiliary transformer are connected, in series and in oppo- 105 110

sition to each other, across two adjacent primary taps and to one side of the supply circuit. Next, the first secondary coil and the first primary tap are disconnected from the supply circuit by the transfer switch, leaving the second coil of the auxiliary transformer and the second tap of the main transformer connected to the supply circuit. At this time, the second coil of the secondary winding of the auxiliary transformer has a voltage impressed on it in opposition to the supply circuit voltage which is equal to one-half the voltage existing between two adjacent primary taps of the main transformer. Finally, the voltage impressed on the second coil of the auxiliary transformer by the induction regulator is reduced to zero value so that the second tap of the primary winding is practically connected directly to the supply circuit.

Thus, the change of the supply-circuit connection from one transformer tap to an adjacent transformer tap is effected in a gradual manner to prevent any abrupt changes in the transformer circuit and, accordingly, in the furnace circuit which is connected to the transformer.

In the accompanying drawings, Figure 1 is a diagrammatic view of a furnace-regulator system embodying my invention, and Figs. 2 and 3 are, respectively, side elevational and plan views of the induction regulator, the main transformer and the drum switch shown in Fig. 1 of the drawings.

Referring to the drawings, an electric furnace 1, having a heating resistor 2, is directly connected to the secondary winding 3 of a main transformer 4. The main transformer 4 is provided with an auxiliary winding 7 and a primary winding 5, which is divided into two portions 6 and 8. The primary winding 5 is adapted to be connected across a supply circuit, comprising conductors 9 and 10, by means of a transfer switch 11, a selector switch 12, an auxiliary transformer 13 and an induction regulator 14. The transfer switch 11 embodies a contact segment 15, which engages a contact finger 16 at all times, and a contact segment 17, which is electrically connected to the contact segment 15 and extends slightly more than half-way around the drum upon which the segments 15 and 17 are mounted. The contact segment 17 is adapted to engage two contact fingers 18 and 19 for a purpose to be hereinafter set forth. The auxiliary transformer 13 embodies a primary winding 20 which is connected to the stationary coil 21 of the induction regulator 14, and a secondary winding comprising two coils 22 and 23. If so desired, the auxiliary transformer may be dispensed with and the coils 22 and 23 be embodied as a part of the induction regulator 14.

The selector switch 12 embodies two arms 24 and 25 which are geared together in any suitable manner and respectively, successively engage contact fingers 26 to 30, inclusive, and contact fingers 31 to 35, inclusive. 70 The induction regulator 14 comprises the stationary coil 21, which is connected in series with the primary winding 20 of the auxiliary transformer 13, and a movable coil 36, which is connected in series with the auxiliary winding 7 of the main transformer 4.

One terminal of the portion 6 of the primary winding 5 is directly connected to the supply conductor 10, and the other terminal of this portion of the primary winding is connected to the contact finger 16 of the transfer switch 11. The two contact fingers 18 and 19 of the transfer switch 11 are respectively connected to one terminal of the secondary coils 22 and 23 of the auxiliary transformer 13. The other terminals of the two coils 22 and 23 are respectively connected to the two switch arms 24 and 25 of the selector switch 12. The portion 8 of the primary winding 5 is provided with a plurality of taps 37 to 41, inclusive, which are respectively connected to the contact fingers 26 to 30, inclusive, and a plurality of taps 42 to 46, inclusive, which are respectively connected to the contact fingers 31 to 35, inclusive.

The induction regulator 14, the transfer switch 11 and the selector switch 12 are operated by any suitable motor, such as a three-phase induction motor 47, which is adapted to be connected across a supply circuit comprising conductors 48, 49 and 50 by means of two relays 51 and 52 for operation in a forward and in a reverse direction. 100 The two relays 51 and 52 are adapted to be controlled manually by means of two push buttons 53 and 54, or automatically, in accordance with the current supply to the furnace 1 by means of a main control magnet 55. A double-throw, single-pole switch 56, comprising a switch blade 57 and two contact fingers 58 and 59, is provided for connecting the two relays 51 and 52 for manual operation by the two push-buttons or for automatic operation by means of the main control magnet 55. When the switch blade 57 is connected to the contact finger 58, as illustrated in the drawing, the two relays 51 and 52 are under the control of the main control magnet 55, and when the switch blade 57 is in engagement with the contact finger 59, the two relays 51 and 52 are under the control of the push buttons 53 and 54. The relay 51 serves to connect the motor 47 across the supply conductors 48, 49 and 50 in order to effect rotation of it in a counter-clockwise direction and thus reduce the voltage which is impressed upon the furnace 1, and the switch 52 serves to connect the mo- 130

tor 47 across the supply conductors 48, 49 and 50 so as to rotate it in a clockwise direction and thus raise the voltage impressed upon the furnace 1, as will be hereinafter set forth.

The main control magnet 55 embodies a winding 61, which is connected to the circuit of the furnace resistor 2 by means of a series transformer 62, in order to be energized in accordance with the current flowing through the furnace 1. The winding 61 operates a core armature 63 which is pivotally connected to a contact arm 64. The contact arm 64 is adapted to engage a main contact finger 65 for operating the relay 51 in one position of the main control magnet 55 and to engage a main contact finger 66 for operating the relay 52 in the opposite position of the main control magnet 55. The main control magnet 55 is adapted to be disengaged from the current transformer 62 by means of a switch 67 and the supply circuit, comprising conductors 9 and 10, is adapted to be disengaged from the furnace system by means of a switch 68.

In the operation of my furnace system, it is essential to rotate the moving parts of the transfer switch 11 and the induction regulator 14 at the same speed and to move the switch arms 24 and 25 of the selector switch 12 from one contact finger to a second contact finger during each revolution of the moving parts of the transfer switch 35 and of the induction regulator. One means whereby the above operation of the transfer switch, the induction regulator and the selector switch may be accomplished is illustrated in Figs. 2 and 3 of the drawings. It 40 is to be understood, however, that my invention is in no way limited to such a structure, inasmuch as any other suitable arrangement of gears and rods for obtaining the same sequence of operation of the 45 various parts may be utilized, if so desired.

Referring to Figs. 2 and 3 of the drawings, the movable coil 36 of the induction regulator 12 is mounted upon a rod 75 which is directly connected to the motor 47 50 in any suitable manner, as by means of the worm gearing 76. The rod 75 at the upper end thereof is provided with a double bell crank 77 which, in turn, is connected to two side rods 78 and 79.

The two contact segments 15 and 17 of the transfer switch 11 are mounted upon a contact drum 80 which, in turn, is mounted upon a shaft 81. The shaft 81 is provided with a double bell crank 82, which 60 is similar to the bell crank 77 mounted upon the shaft 75, and is connected to the side rods 78 and 79. The two switch arms 24 and 25 of the selector switch 12 are preferably mounted above the main transformer 65 4 and within the casing 83 which incloses

the main transformer 4. The two switch arms 24 and 25 are respectively connected to two gear wheels 84 and 85 which engage a pinion 86 that is mounted upon a shaft 87. The shaft 87 projects through the 70 transformer casing 83 and is provided with a double bell crank 88, which is similar to the bell cranks 77 and 82. The crank 88 is connected to the side rods 78 and 79, in order to be operated by the motor 47. 75

By the above connection, it is apparent that the drum 80 of the transfer switch 11 and the moving coil 36 of the induction regulator 14 revolve at the same speed and the pinion 86 and the gear wheels 84 and 85 may be so adjusted that the contact arms 24 and 25 move a distance equivalent to the distance between two contact fingers of the selector switch for each revolution of the drum 80 and of the coil 36. 80

In order to explain the operation of my furnace system, it is assumed that a current below normal value is flowing through the furnace 1 and it is desired to increase the voltage impressed on the transformer 4 90 so as to increase the current flow through the furnace. Assuming the contact finger 18 to be engaging the contact segment 17 midway between its extremities, the switch arms 24 and 25 to be in the position illustrated, the movable coil 36 of the induction regulator 14 to be in the position illustrated, and the switch 56 to be in the position illustrated for effecting automatic operation of the system, then the contact arm 100 64 of the main control magnet 55 will be moved to engage the contact terminal 66 by reason of the decreased energization of the winding 61. Upon engagement of the contact arm 64 with the contact finger 66, 105 a circuit is completed from the supply conductor 48 through the switch arm 57, contact terminal 58, contact arm 64, main contact terminal 66 and the energizing coil of the relay 52 to the supply conductor 49. Thereupon, the relay 52 is operated to connect the motor 47 across the supply conductors 48, 49 and 50, in order to operate it in a clockwise direction so as to raise the voltage impressed upon the circuit of 115 the furnace 1.

The motor 47 effects the rotation of the movable coil 36 of the induction regulator 14, the drum 80 of the transfer switch 11, and the switch arms 24 and 25 of the selector switch 12, but the rotation of the coil 36 is the only operation at this time which produces any electrical effect upon the circuit of the furnace. The rotation of the coil 36 increases the voltage of the primary winding 20 of the auxiliary transformer 13, which is impressed upon the two secondary coils 22 and 23 and, accordingly, increases the voltage which is impressed upon the circuit of the primary winding 5 of the main trans- 125 130

former 4. The circuit of the primary winding 5 may be traced from the supply conductor 10 through the switch 68, portion 6 of the winding 5, contact finger 16, contact 5 segments 15 and 17, contact finger 18, secondary coil 22 of the auxiliary transformer 13, switch arm 24, contact finger 26, the complete portion 8 of the winding 5, and the switch 68 to the supply conductor 9. The 10 voltage impressed on the coils 22 and 23 is increased until a value equal to one half the voltage existing between two adjacent taps of the portion 8 of the primary winding 5 is arrived at and, 15 when the movable coil 21 has been rotated through an angle of ninety degrees. Just previous to the quarter revolution of the coil 36, the switch arm 25 of the selector switch 12 engages the contact finger 31, which is 20 connected to the second transformer tap 42 and, when the transfer switch 11 has been rotated through a quarter turn, the switch segment 17 is in engagement with the contact fingers 18 and 19. Accordingly, the two 25 secondary windings 22 and 23 of the auxiliary transformer 13 are connected in opposition to each other through the transfer switch 11 and the portion 6 of the primary winding 5 to the supply conductor 10, and 30 are directly connected across the transformer taps 37 and 42 by reason of the engagement of the contact arms 24 and 25 with the contact fingers 26 and 31. Consequently, the current flowing through the primary winding 5 from the supply conductor 10 may pass either through the secondary coil 22 and the primary tap 31 or through the secondary coil 23, which opposes the voltage of the supply circuit by an amount equal to one 35 half the voltage existing between the primary taps 37 and 42, and the transformer tap 42. Upon further rotation of the transfer switch 11, the switch segment 17 becomes disengaged from the contact finger 18 so as to 40 disconnect the secondary coil 22 and the primary tap 37 from the supply conductor 10. Consequently, the supply conductor 10 is connected through the portion 6 of the primary winding 5, the transfer switch 11 45 and the secondary coil 23 to the second primary tap 42 of the portion 8 of the primary winding 5, with the voltage impressed on the secondary winding 23 opposing the potential of the supply circuit. 50

Upon further rotation of the induction regulator 14, the voltage which is impressed upon the secondary winding 23 is gradually reduced to zero value, and the second tap 42 of the primary winding 5 is connected to the 55 supply circuit without the auxiliary transformer 13 adding to, or subtracting from, the voltage of the supply circuit. At this point, the transfer switch 11 and the coil 36 of the induction regulator 14 have effected 60 one half a complete revolution, and further 65

rotation of the coil 36 of the induction regulator 14 increases the voltage which is impressed upon the secondary winding 23 of the auxiliary transformer 13 but in such direction as to add to the voltage of the supply circuit. Upon further rotation of the coil 36, the voltage impressed upon the secondary coil 23 is raised to a value equivalent to one half the voltage existing between the primary taps 42 and 38. At this time, the 70 transfer switch 11 and the coil 36 of the induction regulator 14 have effected a three-quarter turn, and the contact segment 17 of the transfer switch is in connection with the two contact fingers 18 and 19. Previous to the connection of the contact segment 17 with the contact finger 18, the contact arm 24 of the selector switch 12 has been moved into engagement with the contact finger 27, which is connected to the transformer tap 38. 75 Consequently, the two secondary coils 22 and 23 of the auxiliary transformer 13 are connected in opposition to each other across the transformer taps 42 and 38 so that the current from the supply circuit may flow 80 through either of the secondary coils 22 and 23 and either of the taps 38 and 42 of the primary winding 5. The further rotation of the transfer switch 11 disconnects the contact segment 17 from the contact finger 19 so as to disconnect the secondary coil 23 and the primary tap 42 from the supply circuit. 85 90

Upon further movement of rotation of the coil 36 of the induction regulator 14, the 100 voltage impressed upon the secondary coil 22 is gradually reduced to zero value, as the coil 36 completes a revolution. From the above, it will be noted that, during a complete revolution of the transfer switch 11 105 and the induction regulator 14, the connection of the supply conductor 10 has been transferred from the primary tap 37 of the portion 8 of the primary winding 5 to the transformer tap 38 so gradually as to prevent any abrupt circuit changes. 110

In case the current flowing through the furnace 2 is above normal value, the main control magnet 55 is operated to connect the contact arm 64 with the contact terminal 115 65 and complete a circuit through the energizing winding of the relay 51. Upon operation of the relay 51, the motor 47 is energized for rotation in a counter-clockwise direction in order to rotate the transfer 120 switch 11, the coil 36 of the induction regulator 14 and the contact arms 24 and 25 of the selector switch 12 in a direction the reverse of that heretofore described. Since the reverse operation of the selector switch 12, the transfer switch 11 and the induction regulator 14 is similar to the operation of these parts in a forward direction, a detailed description of such operation is deemed unnecessary. 125 130

In case it is desired to effect manual control of the furnace 1, the switch 56 is reversed so as to connect the switch blade 57 with the contact finger 59 and transfer the control of the relays 51 and 52 from the main control magnet 55 to the push button switches 53 and 54, the push button 53 serving to operate the relay 51 to increase the voltage impressed upon the furnace, and the push button 54 serving to operate the relay 52 to raise the voltage which is impressed upon the furnace.

Modifications in the system, and in the arrangement and location of parts may be made within the spirit and scope of my invention and such modifications are intended to be covered by the appended claims.

I claim as my invention:—

1. In a regulator system, an electric furnace, a supply circuit, a transformer for connecting the furnace to the supply circuit, and means, comprising an induction regulator, for varying the number of effective turns included in said transformer.

2. In a regulator system, an electric furnace, a transformer having a primary and a secondary winding, said primary winding having a plurality of taps extending from it and said secondary winding being connected to said furnace, a supply circuit, and means, comprising an induction regulator, for governing the connection of the supply circuit to the transformer taps and for shifting the supply circuit connection from one tap to another tap without any abrupt circuit changes.

3. In a regulator system, an electric furnace, a supply circuit, a transformer having a plurality of taps extending from it and serving to connect the furnace to the supply circuit, and means, comprising an induction regulator, for changing the connection of the supply to the various transformer taps to maintain the power input into the furnace substantially constant.

4. In a regulator system, an electric furnace, a supply circuit, a transformer having a plurality of taps extending from it and serving to connect the furnace to the supply circuit, an induction regulator, an auxiliary transformer, and means, comprising said regulator and the auxiliary transformer, for connecting the supply circuit to the various transformer taps without any abrupt circuit change.

5. In a regulator system, an electric furnace, a supply circuit, a transformer for connecting said furnace to the supply circuit, and means, comprising an inductive device, for varying the number of effective turns included in said transformer to regulate the furnace.

6. In a regulator system for an electric furnace, a furnace resistor, a supply circuit, a transformer having a plurality of taps ex-

tending from it and serving to connect the resistor to said supply circuit, and means, comprising an induction regulator, for selectively connecting the various transformer taps to the supply circuit to regulate the circuit conditions of said resistor.

7. In a regulator system, an electric furnace, a supply circuit, a transformer connected to the electric furnace and having a plurality of taps extending from it, means, comprising an induction regulator, for connecting the transformer to the supply circuit, and means for varying the connections of the regulator to the transformer taps to control the furnace and to prevent any sudden changes in the circuit connections.

8. In a regulator system, a transformer having a primary and a secondary winding, a plurality of taps extending from said primary winding, an electric furnace connected to said secondary winding, an induction regulator connected to said primary winding and means for varying the connection of said regulator to the transformer taps to regulate the operation of the furnace.

9. In a regulator system, a transformer having a plurality of taps extending from the winding thereof, a supply circuit connected to the transformer, means, comprising an induction regulator, for changing the supply-circuit connections between the various transformer taps, and means for automatically controlling the operation of the induction regulator in accordance with certain circuit conditions of the transformer.

10. In a regulator system, a transformer having a primary and a secondary winding, said primary winding having a plurality of taps extending from it, a supply circuit adapted to be connected to the transformer, means, comprising an induction regulator, for changing the connection of the supply circuit from one to another transformer tap, and means for automatically operating said induction regulator in accordance with the current flowing in the transformer.

11. In a regulator system, a furnace resistor, a transformer comprising a secondary winding connected to said resistor, and a primary winding having a plurality of taps extending from it, an induction regulator adapted to be connected to said transformer taps, and automatic means for varying the connection of said regulator to maintain a constant current flow through the furnace resistor.

12. In a regulator system, a furnace resistor, a transformer connected to said resistor and having a plurality of taps extending from it, a supply circuit, means, comprising an induction regulator, for governing the connection of the transformer taps to said supply circuit, and automatic means for operating said induction regulator in accord-

- ance with the current flowing through the furnace.
13. In a regulator system, a supply circuit, a main transformer having a plurality of taps extending from it, an auxiliary transformer having a primary winding and a plurality of secondary coils, means for selectively connecting said secondary coils in series with the various transformer taps across the supply circuit, and means, comprising an induction regulator connected to the primary winding of the auxiliary transformer, for varying the voltage of said secondary coils to permit the transfer from one transformer tap to another transformer tap without any abrupt circuit changes. 60
14. In a regulator system, a supply circuit, an electric furnace, a main transformer connected to said furnace and having a plurality of primary taps, and means comprising an auxiliary transformer and an induction regulator, for connecting the supply circuit to the various taps of the main transformer to control the operation of the furnace without any abrupt circuit changes. 70
15. In a regulator system, a main transformer having a primary and a secondary winding, a plurality of taps extending from said primary winding, an auxiliary transformer having a primary winding and a secondary winding comprising two coils, means for successively connecting the secondary coils of said auxiliary transformer in series with said transformer taps, and means, comprising an induction regulator connected to the primary of said auxiliary transformer, for varying the voltage impressed on said secondary coils to permit the transfer from one transformer tap to a second transformer tap without any abrupt circuit changes. 80
16. In a regulator system, a main transformer having a plurality of taps extending from the primary winding thereof, a supply circuit, an auxiliary transformer having two floating secondary coils for connecting the supply circuit to said primary taps, and means for connecting said floating coils jointly in opposition to each other and severally between the supply circuit and the transformer taps to change the supply circuit from one to another transformer tap without any abrupt circuit change. 90
17. In a regulator system, a main transformer having a plurality of primary taps, an auxiliary transformer having two secondary windings adapted to be connected in opposition to each other and a primary winding, an induction regulator connected to the primary winding of the auxiliary transformer for varying the voltage impressed on said secondary windings, and means for successively connecting said secondary windings to the primary taps of the main transformer. 100
18. In a regulator system, the combination with a supply circuit, an electric furnace, a main transformer connected to said furnace and having a plurality of taps extending from the primary winding, and an auxiliary transformer having two floating coils adapted to be connected between said transformer taps and the supply circuit, of means for varying the voltage impressed on said floating coils and for varying the connections of the coils to the transformer taps to connect the supply circuit to the various transformer taps and to control the operation of said electric furnace. 110
19. In a regulator system, a supply circuit, a main transformer having a plurality of primary taps, an auxiliary transformer having two secondary windings and a primary winding, an induction regulator connected to the primary winding of the auxiliary transformer for varying the voltage impressed on the two secondary windings, and means for connecting one of said secondary windings between the supply circuit and one of said primary taps, for connecting the two secondary windings in opposition to each other between two of the primary taps and to the supply circuit, and for connecting the second secondary winding separately between one of the primary winding taps and the supply circuit. 120
20. In a regulator system, a main transformer having a plurality of taps extending from it, a supply circuit having one side connected to the main transformer, an auxiliary transformer having two secondary windings and a primary winding, means connected to said primary winding of the auxiliary transformer for varying the voltage impressed on the two secondary windings, and means for successively effecting the connection of one secondary winding between the supply circuit and one of the primary taps, the connection of the two secondary windings between the two primary taps and to the supply circuit, and the connection of the second secondary winding separately between a primary tap and the supply circuit. 130

In testimony whereof, I have hereunto subscribed my name this 11th day of March 1919.

EDWIN LEHR.
